(57) **CLAIM**

The ornamental design for a glass panel, as shown and described.

DESCRIPTION

FIG. 1 is a perspective view of a glass panel showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a close-up view of the FIG. 5; and,

FIG. 9 is a close-up view of the FIG. 7.

The shade lines in the figures show contour and not surface ornamentation.
